**MUFFLER HAVING TWO PARALLEL BORES WITH
SLOTTED BAFFLES**

Eugene A. Mattie, Metacomett Road,
Scituate, Mass. 02060
Filed Dec. 29, 1967, Ser. No. 694,594

ABSTRACT OF THE DISCLOSURE

A muffler is made using precise specific dimensions varying for different sizes. The muffler is made in two parts each of which can be die-cast. When assembled the muffler consists of two parallel tubes each having eleven baffles therein, each baffle being slightly inclined and having a plurality of slots therethrough aligned with corresponding slots in the other baffles in the tube, the inlet and outlet of the muffler each having a cross-sectional area no greater than the combined areas of the apertures in the initial baffles in the two tubes.

This invention relates to mufflers for internal combustion motors designed so that the compression waves in the exhaust gases cancel one another out, resulting in a smooth discharge flow of gases which is virtually silent. As hereinafter described, the muffler consists of two parts each of which can be die-cast for economic production and which are designed to be secured together to form an inlet orifice expanding into a pair of parallel bores which merge in a common chamber tapering to a discharge outlet orifice. To be effective, the muffler must be formed carefully in accordance with the dimensions given for each specified size.

For a more complete understanding of the invention, reference may be had to the following description thereof and to the drawings, of which:

FIGURE 1 is a perspective external view of a muffler embodying the invention;

FIGURE 2 is a plan view of one of the two parts which are joined to make a complete muffler;

FIGURE 3 is a transverse sectional view, on a larger scale, of the muffler shown in FIGURE 1;

FIGURE 4 is a fragmentary section on the line 4—4 of FIGURE 3; and

FIGURE 5 shows a table of dimensions of mufflers of various sizes embodying the invention.

As indicated in FIGURE 2, the muffler has an inlet orifice 10 which opens into a chamber 12. This chamber branches into two parallel bores 13, 14. Each bore has eleven baffles 16 each of which starts from one side of a bore in a substantially radial direction and curves away from the inlet until it meets a segmental element 18 at the other side of the bore in a substantially axial direction. Each baffle 16 has a number of elongated slots 20, 22, 24, 26 therethrough, these slots being of equal width and extending through the baffle wall in an axial direction. As the several baffles are identical, the corresponding slots

2

in the baffles are axially aligned. Each slot has parallel side edges and semicircular ends. The combined areas of the slots through a wall in each of the bores is preferably equal to but not less than the cross-sectional area of the inlet 10.

5 The discharge ends of the bores 13, 14 merge in a discharge chamber 34 which terminates in a discharge orifice 36.

10 As indicated in FIGURE 4, the baffle walls 16 are inclined a few degrees with reference to planes perpendicular to the axes of the bores. Hence the parts 30 and 32 of the muffler are not identical but are nearly so, owing to the slant of the baffle walls. These parts are designed to be capable of being manufactured by die-casting.

15 The size of a muffler made for an engine will depend on the horse-power of the engine. By making a muffler as illustrated on the drawings and carefully following the dimensions given in the table shown in FIGURE 5, an effective muffler will be had in which the compression 20 waves in the exhaust gases will cancel one another out and a quiet outflow from the discharge outlet will result.

I claim:

25 1. A muffler for use with internal combustion engines, comprising a casing having an inlet orifice and a discharge orifice and forming two parallel bores communicating with said orifices, each said bore having a plurality of baffles therein, each said baffle having a plurality of slots therethrough, the slots in each baffle being axially aligned with the corresponding slots in the other baffles in the same bore.

30 2. A muffler as claimed in claim 1, each said baffle curving from an approximately radial direction at one side of its bore to an approximately axial direction at the other side.

35 3. A muffler as claimed in 1, each said slot being elongated with parallel side edges and semicircular ends.

40 4. A muffler as claimed in claim 1, each said bore having eleven baffles therein.

45 5. A muffler as claimed in claim 2, said baffles being inclined slightly with reference to planes perpendicular to the axes of said bores.

6. A muffler as claimed in claim 5, each said bore having eleven baffles therein.
